UNITED STATES PATENT OFFICE.

WALTER H. LEE, OF WASHINGTON, DISTRICT OF COLUMBIA.

DISPLAY FORM.

Application filed January 20, 1925. Serial No. 3,588.

To all whom it may concern:

Be it known that I, WALTER H. LEE, a citizen of the United States, residing at Washington, in the District of Columbia, 5 have invented certain new and useful Improvements in Display Forms, of which the following is a specification.

This invention relates to a display form of hood-like configuration adapted to conceal 10 the natural hair of the user and to exhibit the effect of the style of hairdressing depicted by the form in association with the face of the person to which the form is applied.

15 It is well known that many styles of bobbed or shingled hair are not suitable to the facial characteristics of the wearer and produce an unattractive effect. The appearance and desirability of any particular style 20 of hairdressing upon the face of an individual wearer cannot be satisfactorily ascertained by merely consulting an illustration of different styles, as the cut and arrangement of the hair must be directly associated with the face and head of the person 25 whose hair is to be dressed and the adaptation of the proper style give a refined and attractive appearance.

To effect such a desirable result I have 30 provided a form of hood bearing the representation of a particular style of hair dressing thereon and adapted to partially enclose the head of the wearer to conceal the natural hair so that the complete effect of the particular style depicted upon the hood may be 35 observed in association with the face. There are many popular styles of bobbed and shingled hair and consequently a series of these forms are provided each representing a 40 different style so that several forms may be successively used to determine the style most attractive to the face of the wearer. This use of a rigid form representing a particular style of hairdressing permits the 45 direct application of such a cutting and dressing of the hair to the face of the person and avoids any conjecture as to the result, as does occur when copying from a photograph or cuts depicting the hairdressing 50 in connection with another type of face.

Where the natural hair is long and is being bobbed in the first instance, it is desirable to cover the hair at the back of the neck so that the effect of the bobbed or

shingled hair at that point can be seen. 55 For this purpose a depending neck cover is provided for the head portion of the form.

The invention has for an object to provide a novel and improved construction of hairdressing form embodying a hood adapted to temporarily conceal the hair of the wearer and finished to represent a different and particular style of hairdressing to determine its effect in association with the face of the wearer. 65

Another object of the invention is to provide a hairdressing form comprising a rigid hood having a depending neck portion extending below the line of the hair represented by the hood and adapted to conceal 70 the natural hair in order that the effect of the dressing represented upon the hood may be observed at the back of the neck.

In the drawing:

Figure 1 is an elevation of the invention 75 applied; and

Figure 2 is a central vertical section upon an enlarged scale.

Like numerals refer to like parts throughout the several figures of the drawing. 80

In the application of the invention this form of hood may be produced of any desired material, preferably of light weight such as papier mâché and of a size suitable for general application to the head of the 85 wearer.

In the form illustrated, the hood 10 is provided at the front with an opening 11 so that the sides of the hood are disposed in close associated relation with the face of the 90 wearer. The bottom of the hood is also open at 12 and the edge of these openings may be suitably reinforced by a wire 13, this being preferably disposed so as to exert a slight inward or lateral tension at the point 14 95 which tends to retain the hood in position. The outer surface of this hood has depicted or represented thereon a particular style of hair cutting or dressing and this may be effected by molding and coloring the outer 100 surface 15 of the material from which the hood is formed, or if preferred natural hair may be attached to the form to produce the desired effect. In the case of a bobbed cut of the hair the hood is formed at the rear 105 with a horizontal portion 16 which also forms a pocket adapted to receive the excess natural hair of the wearer when the

hood is applied but if the hairdressing to be represented comprises a shingled cut such extension is not necessary as the hood would follow the natural outline of the head, as indicated by dotted lines in Figure 2.

The hood is further provided with a depending neck cover 17 at the rear thereof which is of substantially curved outline and sufficient in area to cover the natural hair 10 of the wearer, as shown in Figure 1. This is particularly desirable in observing the effect at the back of the neck as it covers any longer hair at that point so that the line 15 of the bob is clearly defined relative to the neck of the wearer.

It is believed that the construction and usefulness of the hood may be apparent from the foregoing description from which it will be seen that a plurality of such 20 play forms are provided each representing a different type or style of hairdressing, and these may be successively applied to the head of a person in order to determine which style is most attractive and suitable to the 25 facial characteristics of the wearer, and when the style desired has been selected the hood acts as a model to guide the cutting of the hair to correspond therewith. The structure of the hood permits its immediate 30 application and removal without disturbing the hair of the wearer and entirely avoids the uncertainty of determining the style of hair 35 cut from illustrations which are associated with an entirely different type of face from that of the person whose hair is being dressed.

While the specific construction of the hood has been herein described, still the invention is not confined thereto as changes and 40 alterations may be made therein without departing from the spirit of the invention as defined by the appended claims.

Having thus described my invention, what

I claim as new and desire to secure by Letters Patent is:

1. A hairdressing form having a hood portion of stiff material adapted to maintain a fixed configuration to enclose and temporarily conceal the hair of the wearer and finished to represent a particular style of hairdressing to determine its effect in association with the face of the wearer. 45

2. A hairdressing form comprising a rigid hood conformed to enclose and temporarily conceal the hair of the wearer and formed at the back with a projected portion to represent a particular style of hairdressing. 50

3. A hairdressing form having a hood portion adapted to temporarily conceal the hair of the wearer and a depending neck cover extended below the nape of the neck to conceal the natural hair at that point. 60

4. A hairdressing form having a hood portion adapted to temporarily conceal the hair of the wearer, and a concave neck portion extending below the representation of the hair upon the hood and simulating the neck 65 of the wearer.

5. A hairdressing form having a hood of stiff material adapted to maintain a fixed configuration and open at the front and base, and a reinforcing frame carried by the free edges of said hood. 70

6. A hairdressing form having a rigid hood portion open at the front and base, a reinforcing frame carried by the free edges of said hood, a depending neck cover extending below the reinforced edge at the base of the hood, and a horizontal portion 80 extending from said cover to the back of the hood to space said back from the head of the wearer. 75

In testimony whereof I affix my signature.

WALTER H. LEE.
